UNITED STATES PATENT OFFICE.

JOHN V. BEEKMAN, OF PLAINFIELD, NEW JERSEY.

DESIGN FOR A LUBRICATING-BOX FOR FRICTION-DRUMS.

SPECIFICATION forming part of Design No. 25,202, dated February 25, 1896.

Application filed July 5, 1895. Serial No. 555,068. Term of patent 14 years.

To all whom it may concern:

Be it known that I, JOHN V. BEEKMAN, a citizen of the United States, and a resident of Plainfield, in the county of Union and State of New Jersey, have invented a certain new and useful Design for a Lubricating-Box for the Shifting Pin of a Friction Rope-Drum, of which the following is a specification.

Figure 1 is an elevation of one end. Fig. 2 is a plan view, and Fig. 3 is an elevation of the opposite end.

The leading feature of my design consists in a side and bottom inclosure and a bridge-piece spanning said inclosure, said parts being provided at the front end with an inwardly-projecting flange having a central opening and being provided at the rear end with an opening in alignment with but smaller than said first-named opening.

a is the side and bottom inclosure, which is preferably cylindrical in its general contour and provided with a top opening, b, of which b' is the lid.

c is an annular flange projecting inward

from one edge of the inclosure a and forming the circular central opening, d.

e is an annular flange extending inward from the opposite end of inclosure a and forming the circular central opening, f, concentric with the opening d, but smaller than the same.

g, h and i is a bridge-piece spanning substantially the structure described in the last paragraph. This bridge-piece is perforated at j by an opening concentric with the openings d and f. The portions h and i are also 35 perforated parallel with the perforation j by perforations k and l.

What I claim is—

The design for a lubricating-box of a friction-drum herein shown and described. 40

Signed at Coronado, in the county of San Diego and State of California, this 19th day of June, A. D. 1895.

JNO. V. BEEKMAN.
